UNITED STATES PATENT OFFICE.

HENRY JEWETT ORTH, JR., OF SEWICKLEY, PENNSYLVANIA.

TORCH.

1,291,096.

Specification of Letters Patent.

Patented Jan. 14, 1919.

Application filed August 13, 1918. Serial No. 249,655.

To all whom it may concern:

Be it known that I, HENRY JEWETT ORTH, Jr., residing at Sewickley, in the county of Allegheny and State of Pennsylvania, a citizen of the United States, have invented or discovered certain new and useful Improvements in Torches, of which improvements the following is a specification.

The invention described herein relates to improvements in torches for illuminating distant areas, such as the enemies' trenches. The means now generally employed consists of a hollow shell charged with combustible material which is ignited by a fuse. It has been found that a large percentage of such shells will so lodge that the discharge opening rests on the ground thus reducing the illumination. The invention herein described has for its object a construction of torch having a spur or point located in such relation to the opening through which the burning gases escape, that such opening will be uppermost so that the gases will always escape freely. The invention is hereinafter more fully described and claimed.

In the accompanying drawings forming a part of this specification, Figure 1 is a sectional elevation of a torch embodying my improvement and Fig. 2 is a side elevation of the torch having a feathered stem for guiding and steadyng the torch while in flight.

In the practice of the invention, the body of the torch is formed preferably by a sheet metal tube having one end permanently closed. While the closure may be effected in any suitable manner, the closed end weighted and the means employed for supporting the torch in vertical position attached in any suitable manner, it is preferred to employ a pointed pin 2 for supporting means, said pin being made of such size and weight as to insure the torch's dropping in a vertical position and to close the end of the tubular body portion by the large end of the pin. The pin may be secured to the tubular body in any suitable manner, but preferably by forming a boss or head 3 on the end of the pin adapted to fit tightly in the tube and bending the edge of the tube into a groove formed around the base of the boss or head.

The tube is filled up to within a short distance of its upper end with any suitable material known in the art capable of producing, during combustion, a large flame of high illuminating character, as for example

a mixture of magnesium, sulfur and fuse powder. On top of this combustible charge is placed a relatively small quantity of suitable material as fuse powder 4 capable of being ignited by suitable means employed for igniting the charges of shells, etc. In most cases, means operative immediately on the landing of the torch and by percussion are to be preferred, and hence while not limiting the invention thereto, an impact means for igniting the powder are shown herein. A plug 5 is forced into the tube so as to bear on the powder 4. This plug is provided with a socket in which is arranged a block 6 having a small pointed projection 7 on its underside, adapted when the block is shifted, as herein described, to strike a cap 8 charged with fulminate and arranged in a recess in the bottom of the socket and communicating with the powder charge 4. This block 6 is normally supported with its projection 7 out of contact with the cap by a spring 9, which, however, will yield when the movement of the torch is arrested, and allow the projection 7 to strike and ignite the cap.

The block is held within the socket by a thin disk 10 arranged in a depression in the end of the plug and held in position by turning over the edges of the wall of the depression. In order to prevent the accidental movement of the block or hammer, a piece of easily frangible wire 11 is passed through the tube, plug and block as shown in Fig. 1.

This block may be thrown by hand, by a bow or other suitable means, when the area to be illuminated is relatively distant. In order to steady and guide the torch, a feathered shaft 12 may be secured to the torch as shown in Fig. 2. The forward end of the tube being weighted, the torch will land in a vertical position and the point entering the ground will support the torch with the plug end uppermost. When the movement of the torch is arrested, the hammer will have sufficient momentum to shear the safety wire, compress the spring and force the point against the cap, exploding the same. By the explosion of the fulminate and the igniting of the powder, sufficient pressure is generated to force the plug out of the torch so that the flame from the combustible material may issue freely from the open end of the torch.

I claim herein as my invention:

1. A projectable torch having in combination a shell for the reception of a combusti-

ble material, means exterior to the shell and secured thereto for causing the torch when thrown to assume and alight in a substantially vertical position and an inertia means 5 independent of the directing or supporting means operative on the arrest of movement of the torch to ignite the combustible material.

2. A projectable torch having in combination 10 a tubular shell for the reception of a combustible material, means for causing the torch to alight in a substantially vertical position, a plug closing the end uppermost when the torch has alighted and adapted to be forced out by pressure of gas within the 15 shell, and means carried by the plug for igniting the combustible material in the shell.

3. A projectable torch having in combination 20 a shell for the reception of a combustible material, means for maintaining the shell in a substantially vertical position during the combustion of the material in the shell, a plug closing the end uppermost after

the torch has alighted and adapted to be forced out by the pressure of gas within the shell, and means carried by the plug for igniting the combustible material. 25

4. A projectable torch having in combination 30 a tubular shell, a weighted spur or point at one end of the shell, a plug closing the opposite end of the shell and adapted to be forced out by pressure of gases generated within the shell, and means carried by the plug for igniting the combustible material in the shell. 35

5. A projectable torch having in combination 40 a tubular shell, a weighted spur or point at one end of the shell, a plug closing the opposite end of the shell and adapted to be forced out by the pressure of gases generated within the shell and means for igniting the charge carried by the plug and operative on the arrest of the movement of the torch.

In testimony whereof, I have hereunto set my hand.

HENRY JEWETT ORTH, JR.
